Patented Dec. 30, 1913.

UNITED STATES PATENT OFFICE.

MAX COWEN, OF NEW YORK, N. Y.

COMBINED BREECHES AND LEGGINGS.

1,082,737.

Specification of Letters Patent. Patented Dec. 30, 1913.

Application filed December 26, 1912. Serial No. 738,719.

To all whom it may concern:

Be it known that I, MAX COWEN, a citizen of the United States, residing at New York, in the county of New York and State of New York, have invented a new and useful Combined Breeches and Leggings, of which the following is a specification.

This invention aims to provide, as a union garment, a pair of breeches and leggings, adapted for children's wear, or for the use of adults in bicycle-riding, horse back riding and similar out door sports.

The invention aims to provide a device of this character in which the constituent members are assembled in a novel manner to effect a minimum waste of the material.

It is within the scope of the invention to improve generally and to increase the utility of, devices of that type to which the present invention appertains.

With the foregoing and other objects in view which will appear as the description proceeds, the invention resides in the combination and arrangement of parts and in the details of construction hereinafter described and claimed, it being understood that changes in the precise embodiment of invention can be made within the scope of what is claimed without departing from the spirit of the invention.

In the drawing:—Figure 1 shows the invention in perspective; Fig. 2 is a rear elevation; Fig. 3 is a plan of one of the rear sections; Fig. 4 is a plan of one of the front sections; Fig. 5 is a plan of the leg insert; Fig. 6 is a plan of the foot insert; and Fig. 7 is a fragmental perspective showing a slight modification in the invention.

In carrying out the invention there is provided a pair of front sections 1, one of which is shown in outline in Fig. 4. Each front section 1 is provided with a concaved lateral edge 2 and with a convexed, oppositely disposed lateral edge 3. Adjacent its upper edge, the front section 1 is slit as shown at 4 to define tabs 5 and 6, the tab 6 being equipped with a transverse pocket opening 7, formed at any angle desired. The front section 1 terminates at its lower end in an extension 8, at the upper end of which a transverse edge 9 is formed. One longitudinal, lateral edge of the section 1 is denoted by the numeral 10, the edge 10 having a notch 11 therein. The oppositely disposed, lateral edge of the extension 8 is denoted by

the numeral 12, and the lower slant edge 14 of the section 1 serves to define a tongue 15.

One rear section is shown in Fig. 3 and is denoted by the numeral 16. The section 16 is provided at one side with a concaved lateral edge 17 and with an oppositely disposed, convexed lateral edge 18. In its upper end, the section 16 is slit as shown at 19 to define tabs 20 and 21. At its lower end, the section 16 is slit as indicated at 22 to form a relatively long extension 23 and to form a shorter extension 24. One lateral edge of the rear section 16 is denoted by the numeral 25, and the other lateral edge is denoted by the numeral 26, the edge 26 merging into the edge 18 formed upon the extension 23. Below the edge 26 is a laterally projecting lip 27. The inner edge of the extension 24 is denoted by the numeral 28 and the inner edge of the extension 23 is denoted by the numeral 29. The lower edge of the extension 23 is shown at 30 and the lower edge of the extension 24 is shown at 31.

The invention further includes a leg insert 32, shown in Fig. 5, the edges of the insert 32 being denoted by the numerals 34 and 34^a, and by the numerals 35 and 33, the insert 32 terminating at its lower end in a tongue 36.

The invention further includes a foot insert 37, shown in Fig. 6, certain edges of which are denoted by the numerals 38, 39 and 40.

In assembling the parts hereinbefore described, the edges of the slits 19 in the upper ends of the rear sections 15 are stitched together at the waist line as shown at 41 and the slits 4 in the front sections 1 are brought together as shown at 42 and are held by buttons 43, or in any other suitable manner. The edges 17 of the rear sections 16 are connected to form a back seam 44 and the edges 2 of the front sections 15 are connected to form the front seam 45, the seams 44 and 45 uniting at the crotch 46. The long edges 3 of the front sections 1 are united with the edges 18 and 26 of the rear sections 16 to form the outside leg seams 47. The edges 10 of the front sections 1 are united with the edges 25 of the rear section 16 to form the inside leg seams 48. The edges 33 of the leg inserts 32 are united to the edges 9 of the front sections 1 as shown at 49. The upper end of the edge 34^a is secured to the upper end of the edge 12 as shown at 51, the

lower portions of the edges 34^a and 12 being united by a lace cord 50, or by buttons 50^a as shown in Fig. 7. The edge 34 of the leg insert is connected to the lip 27 of the rear section 16 as shown at 60. The edge 38 of the foot insert 37 is secured to the edge 31 of the extension 24, as shown at 52. The edge 39 of the foot extension is secured to the lower portion of the edge 29 as shown at 54. The edge 40 of the foot extension is secured as indicated at 54 to the lower portion of the edge 10. The edges 28 and 29 of the extensions 24 and 23 respectively, are stitched together, as indicated at 55. The garment will present an attractive appearance and will fit closely about the leg of the wearer, the lower portions of the garment forming gaiters, overlapping the shoe of the wearer.

20. What is claimed is:—

1. In a garment comprising breeches and leggings, a rear section including a main extension and an auxiliary extension shorter than the main extension, the adjacent longitudinal edges of which are united; a front section including an extension defining a transverse edge; a leg insert secured at one end to the transverse edge and secured along one side to the main or longer extension of the rear section; and a sepa-

rate foot insert terminally secured to the end of the short auxiliary extension of the rear section and secured along opposite edges to the main long extension of the rear section and to the extension of the front section, the insert extending along the inner face of each legging and part way across the rear face thereof and constituting means for shaping the lower end of the sections into gaiters.

2. A bifurcated garment including legs prolonged to form leggings, the lower edges of the leggings being forwardly extended to form gaiters, the lower edges of the leggings being cut away upon their inner sides and in their rear portions to points adjacent the median lines of the leggings to form recesses; and foot inserts set into the recesses, the inserts serving to shape the gaiters and being removable, the leggings being slit upwardly in their rear portions and adjacent their median lines to permit the leggings to be shaped to receive the inserts.

In testimony that I claim the foregoing as my own, I have hereto affixed my signature in the presence of two witnesses.

MAX COWEN.
